(57) **CLAIM**

We claim the ornamental design for an ultrasound tidal breathing sensor pipe, as shown and described.

DESCRIPTION

FIG. 1 is a front view of an ultrasound tidal breathing sensor pipe showing our new design;

FIG. 2 is a rear elevation view thereof;

FIG. 3 is a top plan view thereof;

FIG. 4 is a bottom plan view thereof;

FIG. 5 is a right side elevation view thereof; and,

FIG. 6 is a left side elevation view thereof.

The broken lines shown in the drawings depict portions of the article that form no part of the claimed design.

1 Claim, 6 Drawing Sheets
